8 Claims. (Cl. 143—103)

This invention relates to improvements in sawmill log turner assemblies.

It is a primary object of the invention to provide a sawmill log turner operable to turn logs of different diameters through an angle of substantially 180 degrees.

It is another object of the invention to provide a sawmill log turner which is operable to positively rotate a log through an angle of substantially 180 degrees in which the log engaging parts of the assembly are not confined to movement in a fixed path to compensate for varying dimensions or irregularities of the log.

Still another object of the invention is to provide a sawmill log turner having a log engaging prong which is maintained in engagement with the log by the weight of the log itself.

Still another object of the invention is to provide a sawmill log turner in which the motion of the log turning parts is controlled to disengage the log engaging parts from the log at the completion of the turning operation.

Other objects and features of the invention will become apparent by reference to the following specification taken in conjunction with the accompanying drawings.

In the drawings:

Fig. 1 is a side elevational view of an exemplary embodiment of the invention;

Fig. 2 is a plan view of the log turner of Fig. 1;

Fig. 3 is a partial side elevational view of the assembly of Fig. 1 taken from the opposite side of the assembly;

Fig. 4 is a side elevational view of the assembly taken from the same side as Fig. 3 showing in full and dotted lines movements of the various parts during the initial portion of the retracting stroke with certain parts broken away;

Fig. 5 (Sheet 1) is a cross sectional view taken on line 5—5 of Fig. 1 showing details of the extensible link assembly;

Fig. 6 is a general side elevational view of the assembly showing the relationship between the turning structure and a log at the start of the turning operation;

Fig. 7 is a view similar to Fig. 6 showing a later stage of the turning operation; and

Fig. 8 is a view similar to Figs. 6 and 7 showing still another stage of the turning operation.

The log turner shown in the drawings is especially designed for use in sawmills to rotate a log L about its longitudinal axis through an angle of 180 degrees.

The log turner includes a fixed frame designated generally 10 which in the particular construction shown includes a pair of rigid side channels 12 braced at either end as by cross pieces 14 welded to the side channels.

A shaft 16 is supported between side channels 12 to rotatably support a sleeve 18, the sleeve 18 being supported for rotation about a horizontal axis. A crank 20 is rigidly welded to sleeve 18 for rotation with the sleeve. A hydraulic motor 22 of conventional construction has its cylinder or casing pivotally connected to fixed frame 10 as by a bracket assembly 24. Piston rod

2

26 of motor 22 is pivotally connected to crank 20 as at 28. Movement of the piston of motor 22 within the cylinder is employed in a conventional manner to rotate crank 20, and hence sleeve 18 about the axis of shaft 16.

At each end of sleeve 18, rigid crank arms 30 are rigidly connected to the sleeve for rotation with the sleeve. At the distal end of each crank 30, a pivot 32 connects a rigid arm 36 to each crank, the arms being 10 rotatable relative to the cranks about a common axis parallel to the axis of sleeve 18.

Arms 36 are rigidly interconnected into a rigid framework by a cross frame member 38 fixedly secured to each arm near its upper end.

A pair of frame members 40 are welded at one end to cross piece 38 and project from the cross piece to support at their outer end a log engaging member 42. Log engaging member 42 is supported for free rotation between frame members 40 upon a shaft 44 which is received within a hub upon the member. Member 42 includes a log engaging point or prong 46, a counterbalancing weight 48 and a log engaging abutment surface 50 located on the opposite side of the axis of shaft 44 from prong 46. Counterbalancing weight 48 is located so that prong 46 is normally maintained in the relationship to its axis shown in Fig. 1—namely below and to one side of the axis.

Since the arm assembly which includes sleeve 34, arms 36, etc., is freely rotatable upon shaft 32, it is necessary 30 to provide structure for controlling the movement of the arm assembly about its pivotal axis. At one side of the frame assembly a lug 52 (Fig. 1) is mounted upon side channel 12 to project upwardly about the channel. An elongated slot 54 receives a pivot pin 56 which rotatably supports one end of an extensible link assembly 35 designated generally 58 upon fixed frame 10.

As best seen in Fig. 5, link assembly 58 includes a first link section 60 which is pivotally supported at one end upon pin 56. A second link section 62 is pivotally supported at one end upon the adjacent arm 36 as by 40 a pivot pin 64. A plurality of guide brackets 66 are fixed to link 62 and project outwardly from one side of the member to define openings within which link 60 is slideably received. Thus, links 60 and 62 are connected to each other so that only sliding linear relative movement may take place between the links.

A stop 68 (Fig. 5) is welded to link section 60, and when engaged by the right-hand end of link section 62 defines a minimum length of the extensible link assembly. This minimum length in turn defines a minimum 50 angular displacement between crank 30 and arm 36.

Since prong 46 is driven into the log during the turning operation, it is desirable, when disengaging member 42 from the log to cause the member to move in a direction in which prong 46 is directly withdrawn from the log. 55 This action is accomplished by the ratchet structure shown in Figs. 3 and 4 which includes a lug 70 welded upon side channel 12 at a location within the arc traversed by crank 30. Lug 70 projects upwardly a substantial distance from side channel 12 to support a pivot pin 72 which in turn supports a link 74 for pivotal movement upon lug 70. The outer end of link 74 is slideably received within a guide assembly 76 mounted upon a ratchet link 78. Ratchet link 78 is pivotally connected to arm 36 as at 80. The coupling between link 74 and ratchet link 78 permits only linear sliding movement of one of the links relative to the other in the same fashion as the relative movement between sections 60 and 62 of the extensible link assembly.

Ratchet link 78 is formed with a series of ratchet teeth 82. The pawl portion of the ratchet assembly includes an arm 84 pivotally supported from side channel 12 as at 86

and normally biased in a direction toward ratchet link 78 by means of a tension spring 88 connected between the lower end of arm 84 and a lug 90 fixed to side channel 12.

As the assembly approaches the fully actuated position shown in Fig. 4, arm 36 travels to its greatest angular displacement away from crank 30. Pawl tooth 92 at the end of arm 84 is biased against the ratchet teeth 82 on link 78 during the final portion of the turning movement, and as the angular displacement of arm 36 from crank 30 increases, finger 92 successively engages teeth 82, pawl tooth 92 moving downwardly along teeth 82 as the angular displacement of arms 36 and crank 30 increase.

When crank 30 is rotated in a clockwise direction in Fig. 4 to return the assembly to its rest position, the geometric relationship of arm 36 and log engaging member 42 to pivotal axis 32 is such that arm 36 would be gravitationally biased in a counterclockwise direction as viewed in Fig. 4. This action would tend to cause tooth 46 to bind with log L. The ratchet structure is operable during the initial portion of retraction of the assembly to maintain the maximum angular displacement achieved between crank 30 and arm 36 during the upper portion of the stroke. Thus, during the initial retraction, prong 46 moves along an arc centered at the axis of shaft 16.

When the assembly has been retracted to the position shown in broken line in Fig. 4, the tension exerted by spring 88 is substantially reduced, hence the force urging pawl tooth 92 against teeth 82 is diminished and further clockwise rotation of crank 30 disengages tooth 82 from pawl tooth 92, thus permitting arm 36 to rotate counterclockwise toward crank 30, the rate of movement being restricted because of the straight line sliding relationship permitted by guides 66 on extensible link assembly 58.

Operation of the log turner may best be appreciated by reference to Figs. 6 through 8 of the drawings. As shown in these figures, the log turner will be mounted in fixed relationship to a conventional log supporting structure which includes a support platform P, a fixed side stop S1 and a movable stop S2 which is mounted for movement in a well-known fashion toward and away from side stop S1. The log L is supported upon the platform P between the two side stops, side stop S2 being adjusted horizontally so that the log is engaged between the side stops. The log is maintained in this position while being sawed, the saw passing through the log to make a vertical cut in approximately the plane indicated at C-C in Fig. 6.

As best seen in Fig. 6, the log turning assembly is located below and to one side of the log which is to be turned. The pivotal axes defined by shafts 15 and pivots 32 and 44 extend parallel to the longitudinal axis of the log L. The turning assembly is located somewhat beyond the ends of the log supports and the end of the log is projected beyond the supports in order that the moving parts of the turning assembly will not engage the various supports P, S1 and S2. Preferably, the turning assembly is located with respect to supports S1 and P so that the normal path of prong pivot 44 passes platform P in approximate alignment with the intersection of the platform and stop S1.

When motor 22 is actuated, by conventional means, to extend piston rod 26 from the motor, crank 30 is driven in rotation in a clockwise direction from the position shown in Fig. 6 to the position shown in Fig. 7. The log engaging parts of the assembly thus initially engage the log in the lower left quadrant of the log as viewed in Fig. 7. Abutment portion 50 is the first portion of the assembly to engage the log and as the strong pivot point 44 is driven upwardly along the path, assembly 42 is rotated to drive prong 46 upwardly into engagement with the log. Prong 46 will engage the log approximately directly below the central axis of the log.

During movement of the assembly from its lower or rest position into engagement with the log, arm 36 is gravitationally biased to maintain the angular displacement between arm 36 and crank 30 at a minimum, thus maintaining extensible link assembly 58 at its minimum length. After the log is engaged by the assembly, the reaction of the log upon arm 36 tends to reduce this angular displacement, however stop 68 prevents this action.

With prong 46 engaged in the log, the normal direction of movement of pivot 44 would be upwardly and to the right. Since the log is held against horizontal movement to the right by stop S2 and gravitationally held against upward movement, further rotation of crank 30 forces prong pivot 44 to be driven in a circular path concentric with the axis of the log. In order to accommodate this revised motion of prong pivot 44, the angular displacement between crank 30 and arm 36 increases, the increasing angular displacement being permitted by extension of extensible link 58. There is substantially no resistance exerted by link 58 to movement tending to extend or elongate the link assembly. Since prong 46 is forcibly engaged with the log, movement of prong pivot 44 along the concentric circular path causes the log to rotate in a clockwise direction about its longitudinal axis. Since the normal movement of prong pivot 44 upon clockwise rotation of crank 30 is primarily to the right as viewed in Figs. 6 through 8, prong 46 stays in engagement with the log as the pivot is driven upwardly above the axis of the log.

As prong pivot 44 approaches a position directly above the axis of the log, pawl tooth 92 becomes engaged with teeth 82 of the ratchet assembly (Fig. 4). The maximum angular displacement between crank 30 and arm 36 occurs as prong pivot 44 passes above the log to a location beyond the axis of the log. In order to maintain engagement with the log as prong pivot 44 moves to the position of Fig. 8, the angular displacement between crank 30 and arm 36 would have to decrease, however, the engagement between pawl tooth 92 and ratchet teeth 82 prevents such a decrease in angular displacement and hence as prong pivot 44 approaches the position shown in Fig. 8, continued rotation of crank 30 in a clockwise direction begins to drive prong pivot 44 away from the log. Continued clockwise rotation of crank 30 disengages prong 46 from the log as the prong reaches a position approximately directly above the axis of the log. Since the prong 46 has been in engagement with the log through approximately 180 degrees, the log has turned through approximately 180 degrees.

During the retracting movement of the assembly by reversal of the stroke of motor 22, crank 30 is rotated in a counterclockwise direction. Pawl tooth 92 remains in engagement with the ratchet until crank 30 is lowered beyond the position indicated approximately in dotted lines in Fig. 4. At this time, ratchet arm 84 is no longer forcibly biased toward arm 78 by spring 88 and tooth 92 becomes disengaged from ratchet teeth 82. Arm 36 is then gravitationally urged to pivot toward arm 30, thus returning the parts to the position shown in Fig. 1 as crank 30 reaches its lower rest position.

While a particular embodiment has been described, it will be apparent to those skilled in the art that the disclosed embodiment may be modified. Therefore, the foregoing description is to be considered exemplary rather than limiting and the true scope of the invention is that defined in the following claims.

We claim:

1. A sawmill log turner comprising a fixed frame, a crank assembly mounted in said frame for pivotal movement about a horizontal first axis, means on said frame for rotating said crank assembly between a rest position wherein said crank assembly is inclined below the horizontal and an actuated position wherein said crank assembly is inclined above the horizontal, an arm assembly pivotally mounted at the outer end of said crank

assembly for rotation upon said crank assembly about a second axis parallel to said first axis, said arm assembly being inclined upwardly from said second axis in a direction toward said first axis, a log engaging member including a prong mounted at the upper end of said arm assembly for rotation about a third axis parallel to said first axis, means counterbalancing said log engaging member to normally maintain said prong facing away from said arm assembly at a location below said third axis, a log engaging abutment portion on said log engaging normally located above said third axis, said surface and said prong facing away from said arm assembly to operatively engage a log supported in the path of movement of said member with the longitudinal axis of the log extending parallel to said first axis, said arm assembly being normally gravitationally biased to rotate about said second axis in a direction toward said crank assembly, and extensible link means pivotally coupled between said frame and said arm assembly for controlling the angular relationship between said arm assembly and said crank assembly during movement of said crank assembly between said rest and said actuated positions.

2. A sawmill log turner comprising a fixed frame, a crank assembly supported at one end on said frame for pivotal movement about a horizontal first axis, means for driving said crank assembly in pivotal movement about said first axis between normal rest position and an elevated position wherein said crank assembly is inclined upwardly from said axis, an arm assembly supported at the opposite end of said crank assembly for pivotal movement relative to said crank assembly about a second axis parallel to said first axis, said arm assembly being inclined upwardly from said second axis and gravitationally urged toward a minimum angular displacement from said crank assembly, freely extensible link means connected between said frame and said arm assembly at a location intermediate the ends of said arm assembly, means on said link means for establishing a minimum length of said link means to thereby establish a minimum angular displacement between said crank assembly and said arm assembly, log engaging means mounted at the upper end of said arm assembly facing outwardly from said assembly to operatively engage a log supported in the path of movement of said log engaging means with the axis of said log extending parallel to said first axis, and means operable when said crank is adjacent said elevated position for preventing pivotal movement of said arm assembly about said second axis toward said crank assembly.

3. A sawmill log turner as defined in claim 2 wherein said means operable when said crank is adjacent said elevated position comprises a second extensible link means connected between said frame and said arm assembly, ratchet means on said second extensible link means, and pawl means on said frame engageable with said ratchet means while said crank assembly is adjacent said elevated position to maintain said second extensible link means at the maximum extension of said second extensible link means incurred during movement of said crank assembly adjacent said elevated position, said pawl means being disengageable from said ratchet upon movement of said crank assembly below a selected angle above the horizontal.

4. A sawmill log turner comprising a fixed frame, a crank assembly supported at one end on said frame for pivotal movement about a horizontal first axis, means for driving said crank assembly in pivotal movement about said first axis between a normal rest position and an elevated position wherein said crank assembly is inclined upwardly from said first axis, a pair of rigidly interconnected horizontally spaced parallel arms mounted at one end on said crank assembly for pivotal movement about a second axis parallel to said first axis, said arms being inclined upwardly from said second axis and gravitationally biased toward a minimum angular displacement from said crank assembly, log engaging means pivotally

supported at the upper end of said arms for rotation about a third axis parallel to said first axis, said log engaging means including a prong and a log engaging abutment facing outwardly from said arms to operatively engage the log supported in the path of movement of said log engaging means with the longitudinal axis of said log extending parallel to said first axis, freely extensible link means pivotally connected at one end to said frame adjacent said first axis and pivotally connected at the opposite end to one of said arms, means on said link means defining a minimum length of said link means to thereby establish a minimum angular displacement between said arms and said crank assembly, a second extensible link means pivotally connected at one end to said frame adjacent said first axis and pivotally connected at the opposite end to the other of said arms, ratchet means on said second extensible link means, pawl means on said frame engageable with said ratchet means when said crank assembly is adjacent said elevated position to maintain said second extensible link means at the maximum extension incurred during movement of said crank assembly adjacent said elevated position, said pawl means being disengageable from said ratchet means upon movement of said crank assembly toward said normal rest position.

5. For use in combination with a sawmill having means for supporting a log with the axis of the log extending in a horizontal direction; a log turner assembly comprising a vertically inclined arm, a log engaging member mounted upon a pivot at the upper end of said arm for pivotal movement relative to said arm about a first axis extending parallel to the axis of a log supported on the sawmill, a prong and an abutment surface on said log engaging member facing outwardly of said first axis from said arm and normally disposed in a rest position wherein said prong is located below said first axis and said abutment surface is located above said first axis, pivotal support means at the lower end of said arm supporting said arm for pivotal movement about a second axis parallel to said first axis, and means for driving said pivotal support means from a lower rest position to an elevated actuated position to drive said log engaging member along a path of movement wherein said pivot is driven toward the axis of said log until said prong and said abutment surface are engaged with the log and is subsequently driven upwardly around the axis of the log with said prong fixedly engaged with the log until the log has been rotated about its axis through an angle of approximately 180°.

6. A sawmill log turner comprising a frame, a crank pivotally mounted at one end on said frame for pivotal movement about a horizontal first axis, means for rotating said crank about said first axis between a normal rest position wherein said crank is inclined downwardly from said first axis and an actuated position wherein said crank is inclined upwardly from said first axis, said rest position and said actuated position of said crank being located on the same side of a vertical plane passing through said first axis, an arm pivotally connected at one end to the other end of said crank for pivotal movement about a second axis parallel to said first axis, said arm being inclined upwardly from said second axis toward said plane whereby said arm is gravitationally biased about said second axis toward said crank, means for establishing a minimum angular displacement between said arm and said crank about said second axis, a log engaging member mounted upon the upper end of said arm for pivotal movement about a third axis parallel to said first axis, said member including a prong, a log abutment surface angularly displaced about said third axis from said prong, and a counterweight for normally locating said surface and said prong facing away from said arm with said prong located below said surface to operatively engage a log supported in the path of movement of said member with the axis of said log extending parallel to said first axis, and means operable when said crank is located ad-

jacent said actuated position for preventing movement of said arm about said second axis in a direction toward said crank.

7. A sawmill log turner as defined in claim 6 wherein said means for establishing a minimum angular displacement of said arm from said crank assembly comprises extensible link means including a first link pivotally connected to said frame and a second link pivotally connected to said arm, means connecting said links to each other to confine relative movement of said links to linear sliding movement and stop means on one link engageable with the other link to define a minimum length of said link means.

8. A sawmill log turner as defined in claim 7 wherein

5 said means operable when said crank is located adjacent said actuated position comprises ratchet means connected between said frame and said arm for preventing pivotal movement of said arm about said second axis toward said first axis during the initial portion of movement of said crank from said actuated position toward said rest position.
